(57) **CLAIM**

The ornamental design for a wheeled screen, as shown and described.

DESCRIPTION

FIG. 1 is a top right front perspective view of the first embodiment of a wheeled screen showing my new design; FIG. 2 is a top left rear perspective view of FIG. 1;

FIG. 3 is a front view of FIG. 1;

FIG. 4 is a rear view of FIG. 1;

FIG. 5 is a right side view of FIG. 1;

FIG. 6 is a left side view of FIG. 1;

FIG. 7 is a top view FIG. 1;

FIG. 8 is a bottom view FIG. 1;

FIG. 9 is a top right front perspective view of the second embodiment of a wheeled screen showing my new design; FIG. 10 is a top left rear perspective view of FIG. 9;

FIG. 11 is a front view of FIG. 9;

FIG. 12 is a rear view of FIG. 9;

FIG. 13 is a right side view FIG. 9;

FIG. 14 is a left side view of FIG. 9;

FIG. 15 is a top view of FIG. 9; and,

FIG. 16 is a bottom view of FIG. 9.

The broken line portion of the figure drawings is included to show portions of the article that form no part of the claimed design.

1 Claim, 16 Drawing Sheets
